ROSS O. SHAW, OF MONTREAL, QUEBEC, CANADA, ASSIGNOR TO CANADIAN CAR & FOUNDRY COMPANY, LIMITED, OF MONTREAL, CANADA.

REPAIR KING POST FOR BOLSTERS.

1,425,703.

Specification of Letters Patent. Patented Aug. 15, 1922.

Application filed November 23, 1920. Serial No. 426,030.

To all whom it may concern:

Be it known that I, Ross O. SHAW, a citizen of the United States, and resident of the city of Montreal, in the Province of Quebec and Dominion of Canada, have invented certain new and useful Improvements in Repair King Posts for Bolsters, of which the following is a full, clear, and exact description.

This invention relates to improvements in truck bolster construction and particularly to improvements in construction of king posts for use in the manufacture or repair of truck bolsters. The primary object of the invention is to provide a king post adapted for insertion in a bolster without the necessity of taking apart the compression and tension members.

At the present time bolsters are rendered useless either by reason of the king post breaking or by reason of the members of the bolster stretching or buckling, with the result that the bolster becomes loose and ratty and constitutes a yielding structure in place of the desired rigid structure. The bolsters usually comprise a channel compression member and a tension member in the form of a flat plate, although many bolsters are found with tension members of circular, channel or other cross sections. In order to replace a broken king post, it is necessary to take the bolster apart and, in the case of a bolster having a flat plate tension member, this involves the cutting out of rivets and the unbending of the tension member to disengage same from the compression member. The same applies to bolsters having certain other types of tension members but does not as a rule apply to bolsters having tension members of circular cross section, as such tension members are usually held by nuts. The operations of cutting out the rivets and taking apart the bolster do not improve the strength of the members and require such an expenditure of time and labor that very little is saved over the cost of a new bolster. When a bolster becomes loose from change in the length of its members, it can be tightened up only by inserting a longer king post. The driving of shims between the king post and one of the members is not to be tolerated and, as a new king post can be inserted only by taking the bolster apart, the same expense is incurred as if the king post was broken. This condition does not obtain with bolsters in which the tension members are secured by

nuts, since the bolster may be tightened up as desired. The present invention aims to provide a king post which may be inserted in a bolster either to replace a broken king post or to tighten up the bolster without taking apart the compression and tension members thereof. The invention therefore applies particularly to bolsters of types wherein the compression and tension members are not adjustably connected.

The present invention resides in the king post which is constructed in a plurality of parts, two at least of which meet in a plane out of normal to the axis of the post, so that proper relative movement of the parts exerts a wedging action for the purpose of elongating the post between the compression and tension members.

In the drawings which illustrate the invention:—

Fig. 1 is a partial plan view of a bolster of the form to which the present invention is applicable.

Fig. 2 is a side elevation of a king post formed according to this invention.

Fig. 3 is a section thereof on the line 3—3 Figure 2.

Fig. 4 is a diagram illustrating a king post designed for another type of bolster.

Fig. 5 illustrates a slight modification of king post construction.

Referring more particularly to the drawings, 11 designates the compression member of a bolster, which is shown as of channel cross section, and 12 the tension member of the bolster, which is shown in Figures 1 to 3 inclusive as formed of a flat plate bent at its ends over the ends of the compression member and secured by any suitable number of rivets 13. The king post, designated as a whole by the numeral 14, is inserted between the compression and tension members midway between the ends thereof and forms a truss of the whole structure. The king post is held against movement longitudinally of the bolster by rivets 15 which connect it to the compression member and is held against movement transversely of the bolster by reason of its engagement between the flanges of the channelled compression member. In the simple form illustrated in Figures 1 to 3, there is no connection between the king post and tension member either by way of rivets or flanges on either member engaging the other. In Figure 4, there is illustrated

a king post embraced between flanges of a channel-shaped tension member 12^a and, in Figure 5, there is illustrated a king post having thereon flanges to embrace a tension member of any suitable section.

In all the forms illustrated, the king post comprises a plurality of members of which one member, designated 16, replaces the upper end of the ordinary king post and is connected to the compression member by the rivets 15. The remainder of the king post is formed of one or more members according to the type of post or the type of bolster. In the simple form of bolster the remainder 15 of the post is a single member 17 adapted for engagement with the tension member and with the member 16. The meeting faces 18 of these members are inclined out of normal to the axis of the king post, as clearly 20 shown in Figure 2, the inclination being in the transverse direction of the bolster. These meeting faces are preferably formed on plates 19 which extend without a break through the full cross section of the king 25 post at the plane of meeting. These plates are supported not only by the peripheral frame 20 of the post parts but also by suitably disposed webs 21. In order to avoid any slippage of the parts 16 and 17 in the 30 longitudinal direction of the bolster, one of the plates 19 is grooved as at 22 and the other plate is provided with a rib 23 adapted for engagement in the groove. It is immaterial upon which of the members the 35 groove is formed.

When it is desired to replace a broken king post or tighten up a loose bolster, the old king post is first broken out, the rivets holding it to the compression member being 40 of course removed. The part 16 or head of a king post according to this invention is then applied to the compression member and secured by bolts or rivets 15. The small end of the foot or member 17 is then 45 introduced between the member 16 and the tension member 12, the inclined faces 18 of the two members 16, 17 being in engagement. The member 17 is now pressed into place and being slightly wedge-shaped, as 50 will be readily seen from the drawings, will operate to tighten the bolster. The two parts 16 and 17 are then connected together, to prevent the part 17 backing out, by any suitable number of bolts or rivets 24 connecting the plates 19.

The operation of inserting a king post as described in the preceding paragraph is possible only where the tension member of the bolster is a flat plate or where the specifications of the king post do not require it to embrace the tension member. In such cases, the king post is constructed preferably in three parts, as indicated in Figures 4 and 5, the additional or intermediate part being 65 designated 25 and the foot members 17^a and

17^b. In assembling a king post of this construction, the head and foot members are placed in engagement with the compression and tension members respectively and the intermediate member 25 then driven wedge-wise between them and secured to both. The meeting faces of the wedge and one of the other members will of necessity be inclined or out of normal to the post axis, as described in connection with Figures 1 to 3, in order to obtain the desired wedging action. It will be understood, however, that in the three-piece king post all the meeting faces may be inclined, as is indicated in Figure 4, or that the meeting faces of only two of the parts may be inclined as indicated in Figure 5. The detail structure of the members of the three-piece king post will be substantially the same as the detailed structure of the two-piece post, that is to say, all the parts will preferably have tongue and groove connection. In a three-part king post, it will be possible to drive the intermediate or wedge member in the longitudinal direction of the bolster and it will be understood that, although this method is not as desirable as driving in the transverse direction, it is nevertheless contemplated and included in the following claims.

While the invention may be said to be 95 designed primarily to provide for the repair of damaged bolsters, it will be understood that it may be employed to facilitate the construction of new bolsters, as it will obviate the present necessity of connecting the tension member under necessarily great tension as the members may be connected together first and the king post inserted afterwards. The plate 19 of the upper member 16 of the king post provides a shelf to support the king pin so that a headless pin may be used without any danger of the same falling out or without the necessity of any other means being used to hold the pin in place.

Having thus described my invention, what I claim is:—

1. A king post comprising a body divided transversely into a pair of superimposed parts meeting along a line inclined with respect to the axis of the post and extending entirely across the post.

2. A king post comprising a body divided into a pair of parts, one of which is insertable to extend entirely across the end of the other part to exert a wedging action therebetween and one of the members of the bolster.

3. A king post according to claim 1, including means connecting the parts together to prevent relative movement thereof.

4. A bolster comprising compression and tension members connected at their ends, and a sectional king post inserted between said members, one of the sections of the post

- being designed for insertion last to exert a wedge action to tighten the bolster, the engaging surfaces of said sections being disposed symmetrically about the axis of the 5 post.
5. In combination with a device according to claim 4, means for holding the king post parts against slipping relatively to one another in a direction other than the inserting 10 direction.
6. In combination with a device according to claim 4, means for holding the king post parts against relative movement after insertion.
- 15 7. In combination with a device according to claim 4, means for holding the king post parts against undesirable relative movement during insertion, and means for holding the parts against any relative movement after 20 insertion.
8. A device according to claim 4, in which the parts have tongue and groove connection.
9. A king post comprising an outer peripheral frame formed in a plurality of sections, plates connected between the parts of the frame in each of the several sections, the plates of each part being adapted for engagement with the plates of the adjacent 25 parts, and webs supporting the peripheral frame and said plates.
10. A device according to claim 9 in which the parts of the post separate in planes extending transversely of the post axis.
- 30 11. A device according to claim 9, in which the parts separate in planes extending transversely of the post axis, the plane of separation between two of the parts being out of normal to the axis.
- 40 12. A device according to claim 9, in

which the plates are formed to provide tongue and groove connection between the parts.

13. A king post comprising a pair of members abutting in a plane extending transversely of the post axis, each of said parts including a plate upon which the abutting surfaces are formed, said plate in one of said parts serving as a king pin support, and fastening members connecting said 50 plates.

14. A king post comprising a pair of engaging parts, one being adapted to extend entirely across the inner transverse surface of the compression member, and the other 55 to extend entirely across the inner transverse surface of the tension member, the engaging surfaces of said parts being out of normal to the axis of the post.

15. A sectional king post comprising sections having inclined engaging surfaces and fastening members connecting said sections together and intersecting said engaging surfaces.

16. A king post comprising separate compression and tension member engaging sections, and removable means engaging both of said sections serving to hold said sections engaged with said members.

17. A king post comprising engaging 70 parts having inclined engaging surfaces, a tongue and groove connection between the engaging surfaces preventing lateral shifting thereof, and fastening members intersecting said engaging surfaces and preventing longitudinal shifting thereof.

In witness whereof, I have hereunto set my hand.

ROSS O. SHAW.
